UNITED STATES PATENT OFFICE

109,435

DESIGN FOR A DRESS

Harry Goldman, New York, N. Y.

Application March 16, 1938, Serial No. 75,845

Term of patent 3½ years

To all whom it may concern:

Be it known that I, Harry Goldman, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the specific collar and sleeves in combination with the dress as shown.

I claim:

The ornamental design for a dress, substantially as shown and described.

HARRY GOLDMAN.
